UNITED STATES PATENT OFFICE.

FRANK G. DAVISON, OF BOSTON, MASSACHUSETTS.

ATTACHABLE PLATE AND METHOD OF MAKING THE SAME.

1,425,840.

Specification of Letters Patent. Patented Aug. 15, 1922.

Application filed May 23, 1920. Serial No. 385,248.

To all whom it may concern:

Be it known that I, FRANK G. DAVISON, a citizen of the United States, and resident of Boston, in the county of Suffolk and State of Massachusetts, have invented certain new and useful Improvements in Attachable Plates and Methods of Making the Same, of which the following is a specification.

- 10 This invention relates to sheet metal plates employed for the purpose of exhibiting legible characters on one surface and which have pins or so-called "feet" projecting from the other surface to enable the 15 plate to be attached to another member. Such plates are employed for clock and watch dials, telephone number disks, and elsewhere such as signs or name plates at the entrance of office buildings.
- 20 Plates of the type referred to and most commonly in use are made of sheet metal such as copper, to the back of which the pins or "feet" are secured by soldering. This method of production is expensive and 25 requires great care to ensure correct location of said feet.

The object of the present invention is to provide improved attachable plates which, while having the same appearance as those 30 now in use, are comparatively inexpensive and also stronger. With this object in view the invention consists in a plate having pin-shaped feet which are integral therewith without causing any mutilation of the portion 35 of the plate which carries the usual enamel.

In the accompanying drawings which illustrate one form of plate constructed according to my invention:—

- 40 Figure 1 is a face view of the blank as it is shaped when struck from sheet metal. Figure 2 is a view of the plate from the back thereof after the projecting portions shown in Figure 1 have been given their 45 final shape.

Figure 3 is a view similar to Figure 2 but as the plate appears after the usual enamel coating for bearing legible characters has been applied.

- 50 Figure 4 represents a section on line 4—4 of Figure 1 on a larger scale.

Figures 5, 6 and 7 are views similar to Figure 4 but illustrating successive steps in the operation of producing the article 55 shown in Figure 3.

Figure 8 is an enlarged plan view looking

in the direction of the arrow 8 in Figure 5, and

Figure 9 is a perspective view still further enlarged, illustrating one of the integral feet as it appears when the article is 60 in the condition ready to be enameled.

Similar reference characters designate similar parts of the article in all of the views.

The plate 12, which may be of any size or configuration according to the use to which it is to be put, is stamped or otherwise cut from suitable material such as sheet copper, and when so made the requisite number of marginal projections are formed, such as illustrated in Figures 1 and 4. Each of the integral projections comprises a web 13 terminating in a lip 14 with an intervening narrowed portion or neck 70 15, and said projections are so spaced relatively to each other, and are of such length (especially the webs 13) that when they are altered in shape as presently described the plate will have the required number of feet 80 extending downwardly therefrom at the proper distance from the margin thereof.

After the plate, with its radial projections as described, has been formed, the next step is to roll up the lips 14 and bend 85 them at a right angle to the webs 13 as shown in Figs. 5 and 8. The necks 15 permit this to be done without causing any distortion of the webs 13 out of their normal flat shape. That is, the rolling up of the 90 portions 14 has no effect on the portions 13 which remain flat.

The next step is to bend down the webs 13 close to the line where they meet the margin of the plate and continue said bending until the webs lie flat against the back of the plate. This, as shown in Figs. 2, 6 and 9, causes the lips 14 which are now in the shape of substantially cylindrical pins, to project from the back of the plate 100 to form feet by which the plate may be attached to another member. The final step is the usual one of coating the plate with enamel as indicated at 16 in Figs. 7 and 3. The enamel on the face of the plate, of course, will usually carry the requisite numerals or other designations not necessary to illustrate, but the enamel on the back of the plate serves to aid in holding the webs 13 in the flat positions to which they 110 have been bent. I may also, or alternatively, employ other means for securing the webs

in their flat positions, such as by soldering, but this is rarely advantageous.

It will now be understood that the plate is readily and cheaply made with its feet accurately located, and that the finished article is strong since the feet are integral with the plate itself. And an important feature is that the face of the plate is unmutilated and is therefore capable of being smoothly coated with enamel without requiring any intermediate plate between the plate 12 and the enamel.

It is also to be understood that I do not limit myself to making the article either by hand or by machinery, nor to the particular order which I have described for the successive steps taken during the operation of producing the article.

Having now described my invention, I claim:

1. A plate having marginal portions bent inwardly therefrom and rigidly secured flatwise against the rear surface of the plate, said marginal portions having their tips extending at a right angle to the plate to provide attaching feet.

2. A plate having a continuous unmutilated surface and having marginal portions bent inwardly and secured flatwise against the plate, said marginal portions having their tips extending at a right angle to the plate to provide attaching feet.

3. An attachable plate having marginal extensions bent to provide extremities standing at a right angle to the plate with intermediate portions in contact with the body of the plate.

4. A plate having integral portions bent inwardly from its margin, the ends of said integral portions being substantially cylindrical in form and standing perpendicular to the plate.

5. The method of making a sheet metal article having attaching feet, consisting in forming a blank comprising a plate having marginal extensions, then converting the outer portions of the extensions to substantially cylindrical form and bending said outer portions upwardly relatively to the face of the plate, and then bending the entire extension in the reverse direction to position to locate the cylindrical portions at the back of the plate.

6. The method of making a sheet metal article having attaching feet, consisting in forming a blank comprising a plate having marginal extensions, and then bending said extensions to convert their extremities into attaching feet with intermediate portions in contact with the body of the plate.

In testimony whereof I have affixed my signature.

FRANK G. DAVISON.
